UNITED STATES PATENT OFFICE.

WILLISON H. HAYES, OF TOLEDO, OHIO.

WATER-TIGHT HATCH FOR BOATS.

1,072,611.

Specification of Letters Patent.

Patented Sept. 9, 1913.

Application filed July 2, 1912. Serial No. 707,145.

To all whom it may concern:

Be it known that I, WILLISON H. HAYES, a citizen of the United States of America, residing at Toledo, in the county of Lucas, 5 and State of Ohio, have invented certain new and useful Improvements in Water-Tight Hatches for Boats, of which the following is a specification, reference being had therein to the accompanying drawings.

10 The invention relates to hatch covers for boats, and has for its object the obtaining of a construction which can be easily and quickly opened or closed at any time and which in closed position is water-proof.

15 In the present state of the art hatch coverings formed of wood and also of metal are employed, but where collapsible hatch coverings are employed seepage through the joints has interfered with the construction 20 being water-proof. As a consequence if it is desired to render these hatch coverings perfectly tight it is necessary to batten them down or to cover them with some water-proof material such as tarpaulin. This involves a considerable expense each time the 25 hatches are so water-proofed as well as the inconvenience occasioned by rendering the hatches temporarily inaccessible.

It is the object of the present invention 30 to avoid these objections by providing a construction of telescoping hatch cover, capable of being drawn back at any time to uncover the hatch, and of such construction that when closed all water will be excluded 35 from the hatch opening.

To this end the invention consists in the construction as hereinafter set forth.

In the drawings: Figure 1 is a longitudinal section through a hatch provided with 40 my improved cover. Fig. 2 is a cross section thereof showing one-half of the cover extended and the other half in collapsed condition. Fig. 3 is a perspective view showing detail construction. Fig. 4 is a sectional 45 perspective view, showing the engagement between sections. Fig. 5 is a cross section of the locking means between the two covers.

A is a hatch opening of any area desired and which is surrounded by an inner coaming 50 B and outer coaming C, spaced to form a chamber D therebetween. The lower ends of the front and rear walls of this coaming, conforming to the curvature of the deck or the upper edges thereof, are horizontal.

55 E is a laterally extending flange arranged slightly below the upper edge of the coam-

ing and forming a guide for the sliding and telescoping hatch covers.

The hatch covers are formed of a series of sections F which are preferably of an arch form to produce a drainage pitch from center to sides. At their ends each section is provided with a down-turned flange G resting upon the guide flange E on the coaming and slidably thereupon. The adjacent sections F are proportioned to telescope with each other, so that when all are withdrawn they will occupy a space but slightly greater than that required for a single section, so that the entire area of the hatch opening will 70 be uncovered.

To form a water-tight joint between the adjacent sections a tongue and groove engagement is provided, preferably formed by an angle bar H secured to an upwardly bent 75 flange I at one edge of the section F, the lower flange H' of said angle extending beneath and parallel to the cover to form a returned bend. At the opposite edge of the section an angle flange J is arranged in reverse position or so as to extend above the cover and parallel thereto, and the arrangement is such that the flanges H' and J of adjacent cover sections F will, in the extended position of the latter, interlock with each 80 other and form a double break-joint. To take care of any seepage of water which might force its way through this joint a drain channel L is arranged at the edge of the inner section, and which extends beyond 85 the inner coaming with its ends open to discharge into the chamber D therebetween. This channel may be formed of a channel beam which is riveted to the angle J and down-turned flange M on the section F, and in addition to its drainage function it forms 90 a structural element in imparting strength and rigidity to the cover.

With the construction as described in use, when the covers are extended they will meet 100 at the center of the hatch opening where they may be secured to each other by any suitable lock. In this position the cover will be water-proof, for the reason that any water which may force its way through the joint between the adjacent sections will flow 105 into the drain channel L, which will conduct it beyond the inner coaming and into the chamber between the same and the outer coaming, while any water which forces its way through the joint at the edges of the 110 cover will flow into the same chamber.

Thus by providing a drainage connection with the chamber between the outer and inner coaming the hatch will be practically water-proof.

5 For holding the hatch cover from displacement when in closed position I provide a suitable clamping for the abutting flanges of the sections on opposite sides of the center. This, as shown, consists of a link N and a cam clamping lever O attached thereto and arranged to tightly clamp the flanges of the sections together. It is also necessary to hold the cover from being washed off of the hatch coaming, and for this purpose I have provided cables P secured to ratchet-drums Q at opposite ends of the hatch and at their free ends provided with hooks R for engagement with each other. These cables are drawn over the cover when the latter is closed, being arranged at each side and engaging suitable notches S in the upstanding flanges. Thus to bind down the cover the operator engages the hooks R of the two cables and then tightens them by 25 rotating the ratchet-drum Q until the cable is drawn taut.

For holding the hatch cover when in collapsed position so as to fully clear the hatch opening a foldable guide frame T is arranged in alignment with the guide flanges E, and which will support the sections beyond the coaming. When the cover is extended over the hatch the guides T may be folded upon pivots U so as to be out of the way.

Where it is desired to provide additional securing means for holding down the covers, I may employ the bolts U, which are pivotally secured to a bracket V on the outer 40 coaming and engage angle brackets W on the cover, to which they are secured by nuts X, as shown at the right end of Fig. 2.

What I claim as my invention is:

1. A hatch cover comprising a series of 45 collapsible sections adapted to be extended to cover hatch opening, and drainage means for the joints between adjacent sections permitting of the collapsing of same.

2. A hatch cover comprising collapsible 50 sections, a water arresting means for the joints between sections when in extended position, and means for draining the seepage through said joints to exclude same from the hatchway.

55 3. The combination with a hatchway of a hollow coaming surrounding said hatchway and open at the top, a collapsible hatch cover engaging the outer wall of the coaming and drainage means for the space within 60 the coaming.

4. The combination with a hatchway of a 125 hollow coaming surrounding said hatchway and open at the top, a collapsible jointed hatch cover engaging the outer wall of said coaming, means adjacent to the joints of

said hatchway for draining the seepage therethrough into the chamber within said coaming, and drainage means for said chamber.

5. The combination with a hatchway of a 70 hatch cover therefor, comprising a series of telescoping, overlapping plates, coöperating means upon said plates for producing a break joint therebetween in extended position of the cover, and drainage means for 75 seepage through said joints.

6. The combination with a hatchway of a hollow coaming surrounding same, provided with parallel inner and outer walls, a guide ledge upon the outer walls of said coaming, 80 a hatch cover comprising a series of telescoping, overlapping plates engaging said guide ledge and arching over the hatchway, a break joint connection between the edges of said plates in the extended position thereof, and drainage means for the seepage through said joints into the space between the outer and inner walls of said coaming. 85

7. The combination with a hatchway of a hollow coaming surrounding said hatchway, 90 a hatch cover comprising a series of telescoping, overlapping plates engaging the outer walls of said coaming and arching over said hatchway, return bent flanges on the adjacent edges of said sections in the 95 extended position thereof, and drainage troughs adjacent to said joints for conducting the seepage therethrough in the space between the walls of said coaming.

8. The combination with a hatchway of a 100 hollow coaming surrounding said hatchway, a hatch cover comprising a series of telescoping, overlapping plates and channel bars secured to the inner edges of said plates and extending beyond the inner wall of the 105 coaming with the ends of the channel communicating with the space within said coaming, and break-joints between the overlapping portions of adjacent sections in extended position thereof. 110

9. The combination with a hatchway of a hatch cover therefor comprising a series of telescoping, overlapping plates, coöperating means upon said plates for producing a break-joint therebetween in extended position of the cover, drainage means for the 115 seepage through said joints, and means for binding said cover to the coaming.

10. The combination with a hatchway of a hatch cover therefor comprising a series of 120 telescoping, overlapping plates, a coaming having a guide upon which said plates slide and are supported, and means for binding said plates to the coaming comprising a cable extending from the same and means on 125 the coaming for drawing said cable taut.

11. The combination with a hatchway of a hatch cover therefor, comprising a series of telescoping, overlapping plates, a coaming having a guide flange over which said 130

plates slide and upon which they are supported, and a foldable extension on said guide for supporting the collapsed plates to clear the hatch opening.

5 12. The combination with a hatchway coaming provided with a drainage, of a hatch cover comprising a series of telescoping, overlapping plates engaging the walls of said coaming, break-joints between the overlapping portions of adjacent sections in the

extended position thereof, and drainage means adjacent to said joints for conducting the seepage therethrough to the drainage for the coaming.

In testimony whereof I affix my signature in presence of two witnesses.

WILLISON H. HAYES.
